(57) **CLAIM**

The ornamental design for a container with a flat lid, as shown and described.

DESCRIPTION

This application is being filed concurrently with a design patent application for a Container With a Domed Lid Ser. No. 29/368,437, also invented by the inventors named above.

FIG. 1 is a rear perspective view of a container with a flat lid showing our new design;

FIG. 2 is a rear elevation view thereof;

FIG. 3 is a left side elevation view thereof;

FIG. 4 is a front elevation view thereof;

FIG. 5 is a right side elevation view thereof;

FIG. 6 is a top plan view thereof;

FIG. 7 is a bottom plan view thereof;

FIG. 8 is a front perspective view thereof; and,

FIG. 9 is a bottom perspective view thereof.
